CONTROLLING MECHANISM FOR HYDRAULIC MOTORS.

1,099,238.

Specification of Letters Patent.

Patented June 9, 1914.

Application filed June 20, 1907. Serial No. 379,893.

To all whom it may concern:

Be it known that I, ALBERT V. T. DAY, a citizen of the United States, residing in the borough of Brooklyn, city of New York, 5 in the county of Kings and State of New York, have invented a certain new and useful Improvement in Controlling Mechanism for Hydraulic Motors, of which the following is a specification, reference being had 10 therein to the accompanying drawings, forming a part thereof.

My invention relates particularly to means for governing hydraulic motors which are adapted to operate under substantially constant hydraulic pressure, such, for example, as when the hydraulic motors are connected in parallel relation with each other in a conduit circulatory hydraulic power transmission system, the motors being individually subjected to varying loads, and also required to operate at varying fixed speeds; and the principal object of my invention 20 is to secure delicacy and accuracy of speed regulation or governing of the hydraulic 25 motors operating under such conditions.

Other objects and advantages of my invention will appear from the following description.

My invention comprises improved hydraulic means for determining and regulating the speed of a hydraulic motor, such hydraulic speed-regulating means being controlled by an automatic governor for giving a fixed speed to the motor under 35 varying loads, and the governor in turn being manually controllable so as to change the fixed speed at which the motor operates.

My invention also includes means for employing the above-named hydraulic speed-regulating means for reversing the motor independently of and without interfering with the governing or speed regulation of the motor.

My invention also includes certain other features and details of construction which will appear from the particular description of the embodiment of my invention shown. Such embodiment will now be described with reference to the accompanying drawings, after which I will point out my invention in claims.

Figure 1 is a side elevation, partly in section, of a hydraulic motor, together with the complete hydraulic regulating mechanism, including the automatic governor,

manual governor controlling means and the means for reversing the motor. Fig. 1^a is a detail view showing the reversing valve in its other position or phase from that shown in Fig. 1. Fig. 2 is a longitudinal central vertical section of the hydraulic motor shown in Fig. 1. Fig. 3 is a transverse central vertical section of the same as viewed from the right. Fig. 4 is a diagrammatic representation of a complete system, including three hydraulic motors.

The hydraulic motor shown is of the type which consumes variable quantities of liquid per cycle or during a complete series of operations, for example, for each rotation 70 of a rotary motor, according to the amount of load upon the motor or the amount of work that it is required to do and belongs to the particular class of this type in which the liquid consuming capacity is altered by 75 changing the eccentricity of a rotary piston relatively to its cylinder.

This hydraulic motor has a rectangular casing comprising the flanged side inclosure or frame 1, having downward extensions as 80 shown forming a base or support for the motor, and the end pieces or heads 2 which form also cylinder heads for the motor. The side inclosure and the heads are joined together in a liquid-tight manner with interposed gaskets upon which they are drawn together by bolts as shown. A rotary shaft 3 passes centrally through the heads 2 and has its bearings therein made liquid-tight by packing glands. Externally to the casing the shaft 3 carries a gear wheel 4 for operatively connecting the motor to any tool or mechanism to be driven thereby. Internally of the casing a rotary piston 5 is concentrically fixed upon the shaft 3 as by 85 a key as shown, and fits closely at its ends between the heads 2. The piston is provided with longitudinal channels or grooves in which are located rollers or cylindrical wings 6, the wings being free to move radially in 90 the grooves and, when the motor is in operation, being pressed outwardly by centrifugal force.

The cylinder for the motor comprises a rectangular block 7 embracing the piston 105 and slidably with a close fit in the casing transversely to the axis of the piston. The bore of the cylinder is shown as cylindrical and is of larger diameter than the piston, exclusive of the radially movable wings, 110

which in operation are held in contact with the inner surface of the cylinder by centrifugal force. Relative eccentricity of the piston and cylinder to each other in either one of two opposite directions and to a greater or less desired degree may be produced by sliding the cylinder laterally toward one side or the other of the casing.

The cylinder is provided with an inlet port 8 and an outlet or exhaust port 9 located vertically diametrically opposite to each other. These ports are of sufficient width to always communicate respectively with corresponding inlet and exhaust openings 10 and 11 in the casing at any position of the cylinder. As the piston is intended to rotate in either direction, according to the position of the cylinder, the inlet and exhaust ports respectively extend equally in opposite directions circumferentially of the bore of the cylinder, so as to preserve corresponding relations to the piston in the opposite positions of the cylinder. The exhaust port is of sufficient width to prevent trapping of the exhaust liquid by the rollers or wings of the piston such as would lock the motor.

The lateral sliding movement of the cylinder is limited in each direction by shoulders or lugs located in the path of the cylinder, and shown as formed integrally with the frame 1.

It is evident that the direction of rotation of the piston will be changed by shifting the slide cylinder from one side to the other of the piston. If a motive liquid be supplied to the motor at a constant pressure or at a pressure that does not vary so widely as to be beyond the limits of motor control, then the speed of the motor will depend upon the extent to which the cylinder is shifted away from its middle position. It is obvious that the motor will run at the highest speed or will produce the greatest torque, when the piston eccentricity is greatest. By shifting the cylinder so as to produce different degrees of eccentricity to its piston, the motor may be kept at a constant or fixed speed while doing variable amounts of work, and likewise the motor may be made to operate at different set or fixed speeds regardless of the amount of work that it is doing, within the capacity of the motor.

55 The means for shifting the cylinder to different positions will now be described.
The cylinder is retained at or restored to its middle position or with its bore concentric with the piston by equal opposed resili-
ent means or resisting means, shown as comprising helical compression or thrust springs 12 acting in a lateral direction between the cylinder 7 and its inclosing frame 1. Such mutually opposed springs are shown as eight in number, four at each side, and as re-
60

tained in place by having their ends resting in sockets formed in the cylinder and in the frame. The springs 12 are at all times under opposing tensions and always tend to restore the cylinder to its middle or concentric position and will do so whenever the cylinder is left unrestrained.

Power means are provided for moving the cylinder away from its concentric position in opposition to the springs 12 and to a position of eccentricity with reference to the piston. Such means are shown as hydraulic power means, and include liquid-carrying controlling-pipes 13 and 14 opening into the casing at each side of the slideable cylinder, through openings 15 and 16 in the frame 1. To operate the motor in one of its directions of rotation motive liquid is supplied under pressure through one of the pipes 13 or 14, and acts upon the cylinder as a plunger and in opposition to the springs 12 at the opposite side of the casing, and slides the cylinder over to an eccentric location, as shown in Fig. 3, wherein the cylinder has been moved to the extreme position resulting from the pressure of liquid admitted through the pipe 13. The cylinder will be forced over to a more or less eccentric relation according to the quantity of liquid admitted. If the liquid pressure in the pipe 13 or 14, as the case may be (13 as seen in Fig. 3) be relieved, then the compressed springs will restore the cylinder to its concentric relation, or will partly so restore it, according to the quantity of liquid that is permitted to escape. Hence, to regulate the speed of the motor, pressure-liquid is either supplied to or allowed to escape from the casing through one of the pipes 13 or 14, the other such pipe being left freely open. Pressure-liquid is thus supplied to the one or the other of these pipes according to the direction of motor rotation desired.

The motor receives its supply of motive liquid through a supply-pipe or supply-conduit 17 connected to the inlet 10 of the motor, and the exhaust-liquid leaves the motor through an exhaust-pipe or exhaust-conduit 18 connected to the outlet or exhaust-opening 11.

The pressure-liquid for regulating the speed of the motor is supplied through a regulating-pipe 19 which is connected to either the one or the other of the controlling pipes 13 or 14 according to the position of a four-way reversing valve 20, the other of the controlling-pipes being concurrently connected through the same valve 20 with a relief-pipe 21 opening into the exhaust-pipe 18. The reversing valve 20 is provided with a handle 22 for manual actuation. When the valve 20 is in the position corresponding to the horizontal position of the handle 22, as seen in Fig. 1 and at A and C in Fig. 4, the 130

regulating-pipe 19 will be placed in communication with the controlling-pipe 13 and the controlling-pipe 14 will be placed in communication with the relief-pipe 21 (Fig. 1) and the direction of rotation will be clockwise as viewed from the right of Figs. 1 and 2 and as indicated by the arrow in Fig. 3. When the reversing valve 20 is in the position indicated by the vertical position of the handle 22, as seen in Fig. 1^a, and at B in Fig. 4, then the regulating-pipe 19 will be placed in communication with the controlling-pipe 14 and the controlling-pipe 13 will be placed in communication with the relief-pipe 21 (Fig. 1^a) and the motor will be driven in an opposite direction of rotation to that above noted. In the latter instance pressure-liquid will enter the casing through the controlling-pipe 14 and the cylinder will be forced to the left hand position and to a position of opposite eccentricity to that seen in Fig. 3. It is apparent that the actuation of the reversing valve interferes in no manner with the speed regulation, as in one instance and for one direction of motor rotation speed regulation is effected through the controlling-pipe 13 while the controlling-pipe 14 is freely open, and in the other instance and opposite direction of motor rotation speed regulation is effected through the controlling-pipe 14 while the controlling-pipe 13 is freely open.

The means for supplying and for relieving the liquid pressure in the regulating-pipe 19, to effect the speed regulation of the motor, include a speed-controlling or speed-regulating valve shown as a balanced piston-valve having a cylindrical valve-chamber 23 open to the atmosphere at both ends. Within the valve-chamber 23 are located slideable valve-heads 24 and 25 carried by a valve-stem or actuating-rod 26 extending to the outside of the valve-chamber for actuation of the valves, and shown as supported in and slideable through a bearing formed in a spider carried by one end of the valve-chamber 23. The valve-chamber 23 has three ports or openings at different longitudinal points of its circumference; a medial port 27 and ports 28 and 29 equally longitudinally spaced from and at opposite sides of such medial port. The medial port 27 communicates with the regulating pipe 19; the port 28 communicates with a pressure-pipe 30 leading from the motor supply-pipe 17; and the port 29 communicates with an overflow-pipe 31 opening freely into the exhaust-pipe 18 of the motor. Hence the port 28 forms an inlet for motive liquid to the valve-chamber and the port 29 forms an outlet from the valve-chamber to the exhaust. The inlet 28 is controlled by the valve-head 24 and the outlet 29 is controlled by the valve-head 25, the medial opening 27 being always open into the valve-chamber 23

but sealed away from any other communication when the valve-heads occupy their middle positions. The valve-heads 24 and 25 are spaced such a distance apart on their actuating-rod 26 and are of such a length 70 that in their medial or middle positions the inlet port 28 and the outlet port 29 are both covered (Fig. 1). When the valve-heads are moved to the right the medial port 27 and the outlet port 29 are put in communication with each other through the valve-chamber, the inlet port 28 being closed (B, Fig. 4). When the valve-heads are moved to the left the inlet port 28 and the medial port 27 are put into communication with each other 75 while the outlet port 29 is closed (C, Fig. 4). It is evident without further explanation that when the inlet port 28 is in communication with the medial port 27, motive liquid will pass from the supply-pipe 17 by 80 pressure-pipe 30, valve-chamber 23, regulating-pipe 19, and controlling-pipe 13 or 14, as the case may be, to the casing, and will produce or increase the eccentricity of the cylinder to its piston; and that when the 85 medial port 27 is in communication with the outlet port 29, the springs 12 will reduce or eliminate such eccentricity by forcing the regulating liquid back through the controlling-pipe that is in communication with the 90 regulating-pipe 19 and thence through the valve-chamber and out to the exhaust-pipe 18 by way of the overflow-pipe 31. The extent of movement of the slideable cylinder depends upon the quantity of liquid that is 95 forced into or is permitted to escape from the regulating-pipe 19. In turn the admission of regulating liquid to or the escape of such liquid from the regulating-pipe 19 depends upon the positions of the valve-heads 100 24 and 25, as determined by their common valve-stem 26. To give increased delicacy of regulation the lap of the valve-heads over the ports 28 and 29 toward the middle of the valve-chamber is of small extent when 105 the valve-heads occupy their middle positions, as may be seen in Fig. 1, so that only a slight movement of the valve-stem 26 suffices to effect regulation of the motor.

To prevent sudden, too great or oscillatory 110 movement of the slideable cylinder in the operation of the speed-regulating means such as might cause sudden speed fluctuations in the motor, means are provided for choking or restricting the passageways through the 115 controlling-pipes 13 and 14 so as to produce a dashpot effect upon the cylinder. The choking or restricting means are preferably adjustable, so as to give more or less dashpot effect as desired, and are shown as ordinary globe valves 32 interposed in the controlling-pipes 13 and 14.

To secure a substantially constant motor speed at varying loads the valve-stem 26 is actuated by a speed-influenced governor 120 125 130

shown as of the centrifugal ball type. The governor balls 33 are carried at the ends of the longer arms of bell-crank levers 34 which are pivoted to a collar or governor-whirl 35 fixed on the motor shaft 3. The shorter arms of such bell-crank levers are connected by links 36 with a second collar or governor-head 37 rotatively seated in an annular groove in the enlarged head of the 10 valve-stem 26 which constitutes also a governor-stem and is axially aligned with the motor shaft 3. The centrifugal movement of the governor balls is resisted by a coiled thrust spring 38 surrounding the combined 15 governor-stem and valve-stem 26 and interposed between the enlarged portion thereof and a collar 39 through which the governor-stem is slidably. The collar 39 is retained in stationary position at the desired location 20 by a governor-controlling lever 40.

If it be assumed that the motor is receiving motive liquid at a substantially constant pressure, then so long as the load upon the motor is constant the positions of the 25 governor and speed-controlling valve will not change and will be as shown in Fig. 1. Should the load on the motor be diminished, the tendency of the motor to increased speed will be checked by the centrifugal movement 30 of the governor balls, which will slide the piston-valves 24 and 25 to the right, putting in communication with each other the ports 27 and 29 (B, Fig. 4), and permitting the springs 12 to reduce the eccentricity of the 35 motor piston, as hereinbefore explained, until the speed of the motor becomes steady at the normal rate, when the positions of the governor and controlling-valve as shown in Fig. 1 will be resumed. Should the load 40 upon the motor be increased, the resulting tendency to diminish the speed of the motor will be checked by the sliding to the left of the piston-valves 24 and 25 by the governor spring 38, which will put the ports 28 and 45 27 into communication (C, Fig. 4), permitting the pressure of the motive liquid to increase the eccentricity of the motor piston, until the speed of the motor becomes steady at the normal rate, when the former medial 50 positions of equilibrium of the governor and controlling-valve will be restored, due to the restoring of such normal speed.

It is now apparent that the motor is adapted to and is automatically controlled 55 so as to maintain a substantially fixed speed while operating under varying loads. It is also obvious that variations in the pressure of the motive liquid within certain restricted limits will not vary the speed of the motor, 60 by reason of the operation of the governing mechanism.

As the speed-regulating movements of the 65 slidable cylinder are effected by hydraulic power, such hydraulic power being controlled by the governor, the speed regulation

of the motor is rendered much more accurate and delicate than were the governor itself connected directly to the slidable cylinder. By reason of the fact that the regulating movement of the slidable cylinder under hydraulic controlling pressure is opposed by resilient cylinder-restoring means, such as the springs 12, speed-regulation is much simplified, also the reversing mechanism is simplified and reversal is facilitated without interfering with the speed-regulation. 70

To permit of a change in the fixed or normal speed of the motor, means are provided for manually controlling the automatic governor. These manual governor-controlling means are effective to cause the state of equilibrium (illustrated in Fig. 1) of the governor and of the speed-regulating-valve to occur at whatever speed is desired, within the limits of control. Such a governor, with its manual controlling mechanism may properly be called a variable-speed automatic governor. The manual means for controlling the governor comprise the governor-controlling lever 40 which is pivoted to the slidable collar 39 and has its fulcrum, shown as a slotted pivotal connection, in a stationary bracket 41. For retaining the lever at any desired position against the tension of the spring 38 a stationary rack 42 and pawl 43 with spring 44 are provided. As the spring 38 only acts in one direction, under compression, the teeth of the rack may slope as shown to facilitate convenient manipulation of the lever. If the controlling lever be placed at the extreme right, that position will represent and will result in producing the lowest fixed motor speed for which provision is made, because then the governor spring 38 will be under the least tension, corresponding to a decreased speed of governor and controlling-valve equilibrium. Conversely, if the controlling lever be placed at the extreme left, the highest fixed motor speed will result. Intermediate speeds of the motor may be secured by intermediate positions of the lever 40. As illustrated in the drawings, the set or temporarily fixed speed of the motors would be between the lowest and medium, as indicated by the position of the controlling levers. 90

Supply-valves 45 and 46, shown as ordinary globe valves, are located in the supply-pipe 17, and either one or the other of these 95 valves may be used, or both may be used in conjunction, as desired. It is to be noted that the pressure-pipe 30, leading to the speed-controlling-valve, is connected to the supply-pipe 17 at a point between the valves 45 and 46. If the valve 46 alone is used, then the pressure-pipe 30 is at all times in communication with the motive liquid under pressure, and when the motor is at rest motive liquid will have access to the valve- 100 105 110 115 120 125 130

chamber 23 of the controlling-valve (C, Fig. 4) and will force the slideable motor cylinder over to an extreme eccentric position, as seen in Fig. 3. Under some conditions of service there would be an advantage in this as it enables the motor to start always under full torque. If the valve 45 be used alone then when the motor is stopped pressure of the motive liquid is cut off from the pressure pipe 30 and the motor would probably usually come to rest with its cylinder in a medial or concentric position, or possibly at an intermediate point, according to how much liquid, if any, is left imprisoned in the pipe 30 and its connections. This would result in a more gradual starting of the motor when the motive liquid is again admitted thereto. If, after having stopped the motor by closing the valve 45, it is desired to start the motor under the strongest torque, first the valve 46 would be closed and then the valve 45 opened, to slide the motor cylinder to its most eccentric position, after which the valve 46 would be opened, to start the motor. The automatic governor of course immediately assumes control of the speed as soon as the motor has started.

The motor mechanisms above described are best adapted and are intended to operate under a substantially constant hydraulic pressure, and are especially or particularly intended and adapted to be connected in parallel relation with each other for operation in a hydraulic conduit circulatory system, such as illustrated in Fig. 4, the motors being independently operable and controllable without interference with each other. In such a system a common supply-pipe or feed-conduit 47 communicates with all of the supply-pipes 17, and all of the exhaust-pipes 18 open into a common exhaust-pipe or return conduit 48. Any desired means may be employed for circulating a motive liquid in the system under the conditions required of maintaining a substantially constant circulatory pressure. The means shown comprise an automatically-controlled steam-operated pump for transferring the motive liquid from a receiving tank 49, into which the return-conduit 48 discharges, to a pressure-reservoir 50 from which the feed-conduit 47 leads. The pump has a steam cylinder 51 which receives steam through a steam-pipe 52 controlled by a hand-valve 53, and has a pump-cylinder 54 to which an induction pipe 55 leads from the receiving tank 49 and from which an eduction or delivery pipe 56 opens into the pressure-reservoir 50. To maintain the circulatory hydraulic pressure in the feed-conduit 47, in a substantially constant condition, the pump is controlled by a throttle-valve 57 automatically actuated, in opposition to a spring 58, by pressure in a diaphragm chamber 59, transmitted through a connecting pipe 60

from the pressure-reservoir 50, the upper part of which contains air under the pressure present in the pressure reservoir, the dotted line indicating the liquid level therein. As shown the receiving tank is freely open to the atmosphere through its neck 61.

It is obvious that various modifications may be made in the construction shown and above particularly described within the principle and scope of my invention.

I claim:

1. In combination in a hydraulic power device comprising a plurality of relatively movable coacting parts shiftable relatively to each other to produce different coactive relations of these parts thereby to vary the capacity of the device for motive liquid permitted to pass through the device during a complete series of operations, resilient means tending to maintain the coacting parts in a certain positional relation, and power operated means for shifting the coacting parts relatively to each other in opposition to the resilient means.

2. In combination in a hydraulic power device comprising a plurality of relatively rotary coacting parts shiftable relatively to each other to produce different coactive relations of these parts thereby to vary the capacity of the device for motive liquid permitted to pass through the device per rotation, power operated means for shifting the coacting parts relatively to each other, and resilient means opposed to the power operated means and tending to restore the coacting parts to a certain relative position.

3. In combination in a hydraulic power device comprising a plurality of relatively movable coacting parts shiftable relatively to each other to produce different coactive relations of these parts thereby to vary the capacity of the device for motive liquid permitted to pass through the device during a complete series of operations, resilient means tending to maintain the coacting parts in a certain relative position, and hydraulic power means for shifting the coacting parts relatively to each other in opposition to the resilient means.

4. In combination in a hydraulic power device comprising a plurality of relatively rotary coacting parts shiftable relatively to each other to produce different coactive relations of these parts thereby to vary the capacity of the device for motive liquid permitted to pass through the device per rotation, resilient means tending to maintain the coacting parts in a certain relative position, and hydraulic power means for shifting the coacting parts relatively to each other in opposition to the resilient means.

5. In combination in a hydraulic power device comprising a plurality of relatively movable coacting parts shiftable relatively to each other to produce different coacting

- relations of these parts thereby to vary the capacity of the device for motive liquid permitted to pass through the device during a complete series of operations, resilient means 5 tending to maintain the coacting parts in a certain relative position, power operated means for shifting the coacting parts relatively to each other in opposition to the resilient means, and an automatic governor in 10 control of the power operated means.
6. In combination in a hydraulic power device comprising a plurality of relatively rotary coacting parts shiftable relatively to each other to produce different coactive relations of these parts thereby to vary the capacity of the device for motive liquid permitted to pass through the device per rotation, power operated means for shifting the coacting parts relatively to each other, re- 15 silient means opposed to the power operated means and tending to restore the coacting parts to a certain relative position, and an automatic governor in control of the power operated means.
7. In combination in a hydraulic power device comprising a plurality of relatively movable coacting parts shiftable relatively to each other to produce different coactive relations of these parts thereby to vary the capacity of the device for motive liquid permitted to pass through the device during a complete series of operations, resilient means 20 tending to maintain the coacting parts in a certain relative position, hydraulic power means for shifting the coacting parts relatively to each other in opposition to the resilient means, and an automatic governor in 25 control of the hydraulic power means.
8. In combination in a hydraulic power device comprising a plurality of relatively rotary coacting parts shiftable relatively to each other to produce different coactive relations of these parts thereby to vary the capacity of the device for motive liquid permitted to pass through the device per rotation, resilient means tending to maintain the coacting parts in a certain relative position, hydraulic power means for shifting the coacting parts relatively to each other in opposition to the resilient means, and an automatic governor in 30 control of the hydraulic power means.
9. In combination in a hydraulic power device comprising a plurality of relatively movable coacting parts shiftable relatively to each other to produce different coactive relations of these parts thereby to vary the capacity of the device for motive liquid permitted to pass through the device during a complete series of operations, resilient means 35 tending to maintain the coacting parts in a certain relative position, power operated means for shifting the coacting parts relatively to each other in opposition to the resilient means, and a manually-controllable variable-speed 40 governor in control of the power operated means.
10. In combination in a hydraulic power device comprising a plurality of relatively rotary coacting parts shiftable relatively to each other to produce different coacting relations of these parts thereby to vary the capacity of the device for motive liquid permitted to pass through the device per rotation, power operated means for shifting the coacting parts relatively to each other, re- 45 silient means opposed to the power operated means and tending to restore the coacting parts to a certain relative position, and a manually-controllable variable-speed 50 automatic governor in control of the power operated means.
11. In combination in a hydraulic power device comprising a plurality of relatively movable coacting parts shiftable relatively to each other to produce different coacting relations of these parts thereby to vary the capacity of the device for motive liquid permitted to pass through the device during a complete series of operations, resilient means 55 tending to maintain the coacting parts in a certain relative position, hydraulic power means for shifting the coacting parts relatively to each other in opposition to the resilient means, an automatic governor in 60 control of the hydraulic power means, and a manual device for controlling the governor so as to compel it to become operative at different selected speeds.
12. In combination in a hydraulic power device comprising a plurality of relatively rotary coacting parts shiftable relatively to each other to produce different coactive relations of these parts thereby to vary the capacity of the device for motive liquid permitted to pass through the device per rotation, resilient means tending to maintain the coacting parts in a certain relative position, hydraulic power means for shifting the coacting parts relatively to each other in opposition to the resilient means, an automatic governor in control of the hydraulic power means, and a manual device for controlling the governor so as to compel it to become operative at different selected speeds.
13. In combination in a hydraulic power device comprising a rotary piston and a cylinder for the piston, the piston and cylinder being relatively shiftable toward and away from concentric relation regardless 100 of the rotation of the piston, thereby to vary the rotative coactive relation of the piston and cylinder, resilient means tending to maintain a concentric relation of the cylinder and piston, power means opposed to the resilient means to produce an eccentric relation between the piston and cylinder, and a manually-controllable variable-speed 105 governor in control of the power means.
14. In combination in a hydraulic power 110

device comprising a rotary piston and a cylinder for the piston, the piston and cylinder being relatively shiftable toward and away from concentric relation regardless of the rotation of the piston, thereby to vary the rotative coactive relation of the piston and cylinder, resilient means tending to maintain a concentric relation of the cylinder and piston, power means opposed to the resilient means to produce an eccentric relation between the piston and cylinder in any one of a plurality of directions, manually-controllable reversing means in control of the power means to determine the direction of piston eccentricity, and a manually-controllable variable-speed governor in control of the power means to vary the degree of such eccentricity.

15. In combination in a hydraulic power device comprising a rotary piston and a cylinder for the piston, the piston and cylinder being relatively shiftable toward and away from concentric relation regardless of the rotation of the piston, thereby to vary the rotative coactive relation of the piston and cylinder, resilient means tending to maintain a concentric relation of the cylinder and piston, hydraulic power means opposed to the resilient means to produce an eccentric relation between the piston and cylinder in either of two opposite directions, and manually-controllable reversing means in control of the hydraulic power means to determine the direction of piston eccentricity.

16. In combination in a hydraulic power device comprising a rotary piston and a cylinder for the piston, the piston and cylinder being relatively shiftable toward and away from concentric relation regardless of the rotation of the piston, thereby to vary the rotative coactive relation of the piston and cylinder, resilient means tending to maintain a concentric relation of the cylinder and piston, hydraulic power means opposed to the resilient means to produce an eccentric relation between the piston and cylinder in either of two opposite directions, manually-controllable reversing means in control of the hydraulic power means to determine the direction of piston eccentricity, and a manually-controllable variable-speed governor in control of the hydraulic power means to vary the degree of such eccentricity.

17. In combination in a hydraulic power device comprising a rotary piston, a casing within which the piston has its bearings, and a cylinder for the piston shiftable within the casing transversely to the axis of the piston to produce different amounts of piston eccentricity in either of opposite directions regardless of the rotation of the piston, thereby to vary the rotative coactive relation of the piston and cylinder; resilient

means for moving the cylinder in the casing toward the position of concentric relation of the cylinder and piston.

18. In combination in a hydraulic power device comprising a rotary piston, a casing within which the piston has its bearings, and a cylinder for the piston shiftable within the casing transversely to the axis of the piston to produce different amounts of piston eccentricity in either of opposite directions regardless of the rotation of the piston, thereby to vary the rotative coactive relation of the piston and cylinder; resilient means tending to maintain a concentric relation of the cylinder and piston, and means for subjecting the cylinder to hydraulic pressure to produce eccentric relations between the cylinder and its piston.

19. In combination in a hydraulic power device comprising a rotary piston, a casing within which the piston has its bearings, and a cylinder for the piston shiftable within the casing transversely to the axis of the piston to produce different amounts of piston eccentricity in either of opposite directions; resilient means tending to maintain a concentric relation of the cylinder and piston, passages opening into the casing at each side of the cylinder laterally, means for supplying liquid under hydraulic pressure through such passages to one side or the other of the cylinder to slide the cylinder to an eccentric relation in one direction or the other, and means for adjustably restricting the bores of the passages to produce a damping effect upon the sliding movements of the cylinder.

20. In combination in a hydraulic power device comprising a rotary piston, a casing within which the piston has its bearings, and a cylinder for the piston shiftable within the casing transversely to the axis of the piston to produce different amounts of piston eccentricity in either of opposite directions; resilient means tending to maintain a concentric relation of the cylinder and piston, controlling-passages opening into the casing at each side of the cylinder, a regulating-conduit, and a manually-controllable four-way valve for opening communication between the regulating conduit and either one or the other of the controlling-passages and for concurrently providing a free outlet for the other controlling-passage, whereby the hydraulic pressure will be opposed to the resilient means and will slide the cylinder to one position or the other of eccentricity to its piston according to the position of the fourway valve.

21. In combination in a hydraulic power device comprising a rotary piston, a casing within which the piston has its bearings, and a cylinder for the piston shiftable within the casing transversely to the axis of the piston to produce different amounts of piston eccentricity in either of opposite directions;

resilient means tending to maintain a concentric relation of the cylinder and piston, controlling-passages opening into the casing at each side of the cylinder, a regulating-conduit, a manually-controllable fourway valve for opening communication between the regulating conduit and either one or the other of the controlling-passages and for concurrently providing a free outlet for the other controlling passage, a source of liquid under pressure, and a controlling-valve adapted when in its middle position to seal the regulating-conduit and when moved in one direction to admit pressure-liquid from such source to the regulating-conduit and when moved in the other direction to open a free outlet from the regulating-conduit, whereby movement of the controlling-valve regulates the amount of eccentricity between the cylinder and its piston.

22. In combination in a hydraulic power device comprising a rotary piston, a casing within which the piston has its bearings, and a cylinder for the piston slideable in the casing transversely to the axis of the piston to produce different amounts of piston eccentricity; a controlling-passage opening into the casing laterally of the cylinder, a source of liquid under pressure, a controlling-valve adapted according to its position to seal the controlling-passage or to admit pressure-liquid from such source to the controlling-passage or to open a free outlet from the controlling-passage, and resilient means tending to preserve concentricity of the cylinder and piston in opposition to the hydraulic pressure from the above-named source.

23. In combination in a hydraulic power device comprising a rotary piston, a casing within which the piston has its bearings, and a cylinder for the piston slideable in the casing transversely to the axis of the piston to produce different amounts of piston eccentricity; a controlling-passage opening into the casing laterally of the cylinder, a source of liquid under pressure, a controlling-valve adapted according to its position to seal the controlling-passage or to admit pressure-liquid from such source to the controlling-passage or to open a free outlet from the controlling-passage, resilient means tending to preserve concentricity of the cylinder and piston in opposition to the hydraulic pressure from the above-named source, an automatic governor responsive to speed variations in the motor and for actuating the controlling-valve, and a manual device for controlling the governor so as to render it actuating at any selected motor speed.

24. In combination in a hydraulic power device comprising a rotary piston, a casing within which the piston has its bearings, and a cylinder for the piston slideable within the casing transversely to the axis of the piston to produce different amounts of piston

eccentricity in either of opposite directions; resilient means tending to maintain a concentric relation of the cylinder and piston, controlling-passages opening respectively into the casing at each side of the cylinder laterally, a regulating-conduit, a manually-controllable fourway valve for opening communication between the regulating conduit and either one or the other of the controlling-passages and for concurrently providing a free outlet for the other controlling-passage, a source of liquid under pressure, a controlling-valve adapted when in its middle position to seal the regulating-conduit and when moved in one direction to admit pressure-liquid from such source to the regulating-conduit and when moved in the other direction to open a free outlet from the regulating-conduit, an automatic governor responsive to speed variations in the motor for actuating the controlling-valve, and a manual device for controlling the governor so as to render it actuating at any selected motor speed.

25. In combination in a hydraulic power device comprising a rotary piston, a casing, and a cylinder for the piston slideable in the casing transversely to the axis of the piston so as to change the eccentricity of the piston relatively to the cylinder; resilient means tending to maintain a concentric relation of the cylinder and piston, a controlling-passage opening into the casing laterally of the cylinder, means for supplying liquid under pressure to such passage, and adjustable means for reducing the bore of the controlling-passage so as to damp sudden sliding of the cylinder.

26. In combination in a hydraulic power device comprising a rotary piston, a casing, and a cylinder for the piston slideable in the casing transversely to the axis of the piston so as to change the eccentricity of the piston relatively to the cylinder; resilient means tending to maintain a concentric relation of the cylinder and piston, a controlling-passage opening into the casing laterally of the cylinder, and means for supplying liquid under pressure to such passage, such passage having a restricted portion for checking sudden movements of the cylinder.

27. In combination in a hydraulic power device comprising a rotary piston, a casing, and a cylinder for the piston slideable within the casing transversely to the axis of the piston to produce different amounts of piston eccentricity in either of opposite directions; resilient means tending to maintain a concentric relation of the cylinder and piston, passages opening into the casing at each side of the cylinder, and means for supplying liquid under hydraulic pressure through such passages to one side or the other of the cylinder to slide the cylinder to an eccentric relation in one direction or the

other, such passages having restricted portions for preventing sudden sliding of the cylinder.

28. In combination in a hydraulic power device comprising a rotary piston, a casing, and a cylinder for the piston slideable in the casing transversely to the axis of the piston to produce different amounts of piston eccentricity; a controlling-passage opening 10 into the casing laterally of the cylinder, a supply-conduit for the motor, a pressure-pipe communicating with the supply-conduit, a controlling-valve in control of communication between the pressure-pipe and 15 the controlling-passage, resilient means tending to preserve concentricity of the cylinder and piston in opposition to the hydraulic pressure from the supply-conduit, and a plurality of supply-valves including 20 one in the supply at each side of the point of communication therewith of the above-named pressure pipe.

29. In combination in a hydraulic power device comprising a rotary piston, a casing, 25 and a cylinder for the piston slideable in the casing transversely to the axis of the piston to produce different amounts of piston eccentricity in either of opposite directions; resilient means tending to maintain a con- 30 centric relation of the cylinder and piston, controlling-passages opening respectively into the casing at each side of the cylinder

laterally, a regulating-conduit, a manually-controllable fourway reversing valve adapted when in one position to open communication between the regulating-conduit and one of the controlling-passages while concurrently providing a free outlet for the other controlling-passage and adapted when in its other position to open a free outlet for 40 the last-named controlling-passage, a supply-conduit for the motor, a pressure-pipe leading from the supply conduit, a controlling-valve adapted when in its middle position to seal the regulating-conduit and 45 when moved in one direction to open communication between the pressure-pipe and the regulating-conduit and when moved in the other direction to open a free outlet from the regulating-conduit, an automatic 50 governor responsive to speed variations in the motor for actuating the controlling-valve, a manual device for controlling the governor to render it actuating at different selected motor speeds, and a supply-valve in 55 the supply-conduit at each side of the point of communication therewith of the above-named pressure-pipe.

In testimony whereof I have affixed my signature in presence of two witnesses.

ALBERT V. T. DAY.
